CLAIM

The ornamental design for a cover for a can and bottle insulator, as shown and described.

DESCRIPTION

FIG. 1 is a top perspective view of a cover for a can and bottle insulator showing my new design;

FIG. 2 is a bottom perspective view of the cover for a can and bottle insulator shown in FIG. 1;

FIG. 3 is a top view of the cover for a can and bottle insulator shown in FIG. 1;

FIG. 4 is a bottom view of the cover for a can and bottle insulator shown in FIG. 1;

FIG. 5 is a top perspective view of the cover for a can and bottle insulator shown in FIG. 1 after being installed on a can and bottle insulator;

FIG. 6 is a top perspective view of the cover for a can and bottle insulator shown in FIG. 1 after being installed on a can and bottle insulator containing a can; and,

FIG. 7 is a top perspective view of the cover for a can and bottle insulator shown in FIG. 1 after being installed on a can and bottle insulator containing a bottle.

The dashed lines show portions of the cover for a can and bottle insulator that form no part of the claimed design.
